UNITED STATES PATENT OFFICE

144,418

DESIGN FOR A CREAM MAKER

Howard L. Saylor, Los Angeles, Calif.

Application August 23, 1945, Serial No. 121,594

Term of patent 14 years

(Cl. D23—1)

To all whom it may concern:

Be it known that I, Howard L. Saylor, a citizen of the United States, residing in the city of Los Angeles, county of Los Angeles, State of California, have invented a new, original, and ornamental Design for a Cream Maker, of which the following is a specification, reference being had to the accompanying drawing, forming a part thereof.

I claim:

The ornamental design for a cream maker, as shown.

HOWARD L. SAYLOR.
